US00D909744S

(12) United States Design Patent (10) Patent No.: US D909,744 S
Guo et al. (45) Date of Patent: * Feb. 9, 2021

(54) PILL ORGANIZER

(71) Applicant: ZHUHAI EKTOUCH TECHNOLOGY CO., LTD., Zhuhai (CN)

(72) Inventors: Jinpeng Guo, Zhuhai (CN); Wei Du, Zhuhai (CN)

(73) Assignee: ZHUHAI EKTOUCH TECHNOLOGY CO., LTD., Zhuhai (CN)

() Term: 15 Years

(21) Appl. No.: 29/732,801

(22) Filed: Apr. 28, 2020

(30) Foreign Application Priority Data

Mar. 10, 2020 (CN) 2020 2 0286215

(51) LOC (13) Cl. 03-01

(57) CLAIM

The ornamental design for a pill organizer, as shown and described.

DESCRIPTION

FIG. 1 is a perspective view of a pill organizer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the pill organizer where the pill organizer is in a configuration of use.

The broken lines in the drawings depict portions of the pill organizer that form no part of the claimed design.

1 Claim, 9 Drawing Sheets
